4 Claims

ABSTRACT OF THE DISCLOSURE

2,3-disubstituted - 2,3 - dihydro-6-phenyl-1H-s-triazolo[4,3-a][1,4]benzodiazepin-1-one of the Formula II

wherein R and R₀ are selected from the group consisting of alkyl of 1 to 3 carbon atoms, inclusive, and alkenyl of 3 to 4 carbon atoms, inclusive, wherein R₁ is selected from the group consisting of hydrogen, alkyl of 1 to 3 carbon atoms, inclusive, and alkenyl of 3 to 4 carbon atoms, inclusive; wherein R₂, R₃, R₄, and R₅ are selected from the group consisting of hydrogen, alkyl defined as above, amino, halogen, nitro, cyano, trifluoromethyl, and alkoxy, alkylthio, alkylsulfonyl, and alkylsulfinyl, alkanoylamino, in which the carbon moieties are of 1 to 3 carbon atoms, inclusive, and dialkylamino, in which the alkyl group is defined as above; is prepared by reacting a 2,4-dihydro-1H-s-triazolo[4,3-a][1,4]benzodiazepin-1-one of the formula:

wherein R₁, R₂, R₃, R₄, and R₅ are defined as above, with a base and then with an alkyl halide or alkenyl halide.

The compounds of Formula II and the pharmaceutically acceptable acid addition salts thereof can be used as sedatives and tranquilizers for mammals and birds.

BACKGROUND OF THE INVENTION

Field of the invention

This invention is directed to new organic compounds and is particularly concerned with novel 3-substituted 2,3-dihydro-1H-s-triazolo[4,3-a][1,4]benzodiazepin - 1 - one (II) and a process for the production thereof.

2

The novel compounds and the processes of production therefor can be illustratively represented as follows:

Method A

I

II

Alternative Method B

Alternative Method C

wherein R and R₀ are selected from the group consisting of alkyl of 1 to 3 carbon atoms, inclusive, and alkenyl of 3 to 4 carbon atoms, inclusive; wherein R₁ is selected from the group consisting of hydrogen, alkyl defined as above and alkenyl defined as above; wherein R₂, R₃, R₄, and R₅ are selected from the group consisting of amino, 35 fluoro, chloro, bromo, iodo, cyano, nitro, trifluoromethyl, and alkoxy, alkylthio, alkylsulfinyl, alkylsulfonyl, alkanoylamino in which the carbon moieties are of 1 to 3 carbon atoms, inclusive, and dialkylamino, in which alkyl is defined above, and wherein R' is an alkyl group defined as above.

The invention also encompasses the pharmacologically acceptable acid addition salts thereof.

The process of this invention comprises: (A) reacting a 2,4 - dihydro-1H-s-triazolo[4,3-a][1,4]benzodiazepin-1-one (I) with an alkyl or alkenyl halide in the presence of a base, or, alternatively, (B) heating together a 1,3-dihydro - 5 - phenyl-2H-1,4-benzodiazepine-2-thione with an alkyl or alkenyl substituted carbazic acid ester of the 45 Formula III

wherein R' is alkyl of 1 to 3 carbon atoms, inclusive, and R₀ and R are defined as above, to about 50-100° C. and the resulting product to about 180-250° C. or, alternatively, (c) heating together a 1,3-dihydro-5-phenyl-2H-1,4-benzodiazepine-2-thione with a 1,2-dialkyl or 1,2-dialkenyl hydrazine

wherein R and R₀ are defined as above and treating the intermediate 2 - (1,2-disubstituted-hydrazino-1,4-benzodiazepine with a one carbon dibasic acylating agent of the formula

wherein X and X' are leaving groups, to obtain the compound of Formula II above.

DESCRIPTION OF THE PREFERRED EMBODIMENT

Lower alkyl groups of 1 to 3 carbon atoms, inclusive, are exemplified by methyl, ethyl, propyl, and isopropyl.

Lower alkenyl groups of 3 to 4 carbon atoms, inclusive, are allyl, methallyl and crotonyl.

The carbon chain moiety of alkoxy, alkylthio, alkylsulfonyl, alkylsulfinyl, and dialkylamino is of 1 to 3 carbon atoms, inclusive, and can be defined as lower alkyl of 1 to 3 carbon atoms, inclusive, above.

The alkanoylamino group of 1 to 3 carbon atoms consists of formamido

acetamido and propionamido.

The novel compounds of the Formula II pharmacologically acceptable acid addition salts thereof have sedative, 15 hypnotic, anticonvulsant, tranquilizing, and muscle relaxant effects in mammals and birds. Also as feed additives they are useful to increase growth rate and feed efficiency of livestock and poultry.

The pharmacologically acceptable acid addition salts 20 of compounds of Formula II contemplated in this invention, are the hydrochlorides, hydrobromides, hydriodides, sulfates, phosphates, cyclohexanesulfonates, methanesulfonates and the like, prepared by reacting a compound of Formula II with the selected pharmacologically acceptable acid.

Sedative effects of 8-chloro-6-(o-chlorophenyl)-2,3-dihydro-2,3-dimethyl-1H-s-triazolo[4,3-a][1,4]benzodiazepin-1-one are shown by the following tests in mice:

CHIMNEY TEST

[Med. Exp. 4, 145 (1961)]

The effective intraperitoneal dosage for 50% of mice (ED₅₀) is 11 mg./kg. The test determines the ability of mice to back up and out of a vertical glass cylinder within 30 seconds. At the effective dosage, 50% of the mice failed doing it.

DISH TEST

Mice in Petri dishes (10 cm. diameter, 5 cm. high, partially embedded in wood shavings), climb out in a very short time, when not treated. Mice remaining in the dish for more than 3 minutes indicates tranquilization. ED₅₀ equals the dose of test compound at which 50% of the mice remain in the dish. The ED₅₀ (intraperitoneal administration) in this test was 56 mg./kg.

PEDESTAL TEST

The untreated mouse leaves the pedestal in less than a minute to climb back to the floor of the standard mouse box. Tranquilized mice will stay on the pedestal for more than 1 minute. The ED₅₀ (intraperitoneal administration) is 11 mg./kg.

NICOTINE ANTAGONISM TEST

Mice in a group of 6 are injected with the test compound 8 - chloro - 6-(o-chlorophenyl)-2,3-dihydro-2,3-dimethyl - 1H-s - triazolo[4,3-a][1,4]benzodiazepin-1-one. Thirty minutes later the mice including control (untreated) mice are injected with nicotine salicylate (2 60 mg./kg.). The control mice show overstimulation, i.e., (1) running convulsions followed by (2) tonic extensor fits; followed by (3) death. An intraperitoneal dosage of 9 mg./kg. of the test compound protected 50% of the mice against (2) and (3) (ED₅₀).

The pharmaceutical forms contemplated by this invention include pharmaceutical compositions suited for oral, parenteral, and rectal use, e.g., tablets, powder packets, cachets, dragees, capsules, solutions, suspensions, sterile-injectable forms, suppositories, bougies, and the like. Suitable diluents such as carbohydrates (lactose), proteins, lipids, calcium phosphate, cornstarch, stearic acid, methylcellulose and the like may be used as carriers or for coating purposes. Oil, e.g., coconut oil, sesame oil, safflower oil, cottonseed oil, peanut oil, or water may be used for preparing solutions or suspensions of the active

drug. Sweetening, coloring, and flavoring agents may be added. The acid addition salts may be used in water solutions.

For mammals and birds food premixes, with starch, oatmeal, dried fishmeat, fishmeal, flour, and the like can be prepared. A feed containing from 1-100 g. per ton of feed of compound II or salts thereof is useful to produce faster growth, or higher milk or egg production in farm animals.

As tranquilizer the compounds of Formula II and its 10 pharmacologically acceptable acid addition salts thereof can be used in dosage of 0.01-20.0 mg./kg. in oral or injectable preparations as described above, to alleviate tension and anxiety in mammals, or birds, such as e.g., occurs when animals are shipped. This is not only important for farm animals like cattle, sheep, swine, and house animals, dogs, cats, parrots, but also for many zoo animals during transport.

Other acid addition salts of the compounds of Formula II can be made such as the fluosilicic acid addition salts which although not useful as pharmaceutical products, are useful as mothproofing compounds, or the trichloroacetates useful as herbicides against Johnson grass, Bermuda grass, yellow foxtail, green foxtail, and quack grass.

The starting materials of Formula I of this invention, 25 2,4 - dihydro - 6 - phenyl-1H-[4,3-a][1,4]benzodiazepin-1-ones, are described in British patent specifications 1,254,403; the starting material IA, 1,3-dihydro-5-phenyl-2H-1,4-benzodiazepine-2-thiones, are described by Archer et al., J. Org. Chem. 29,231 (1964). Compounds (II) are made by the reaction of the known substituted or unsubstituted 1,3-dihydro-5-phenyl-2H-1,4-benzodiazepine-2-thiones (IA) with a carbazole as shown in Preparations 1 and 2.

In carrying out the process A of this invention, the starting material of Formula I is treated in a solvent with a strong base. As base sodium hydride, potassium hydride, thallous, sodium or potassium ethoxide, or the like can be used. As solvents dialkyl acid amides or ethers are useful, e.g. dimethyl- and diethylformamide or acetamide, tetrahydrofuran, dioxane, ethylene glycol (or ethylene glycol), dimethyl or diethyl ether, or the like. In the preferred embodiment of this reaction the base is used in a slight excess of the calculated amount such as 10%-25% above the stoichiometric requirement, and the reaction is performed at room temperature or below. However, temperatures of -78 to 50° C. are operational. The time of reaction is between 1 minute and 3 hours, with 15 minutes sufficient, if the reaction is carried out at room temperature. Thereafter the reaction mixture is treated with an alkyl halide or alkenyl halide. Useful alkyl and alkenyl halides are particularly the methyl, ethyl, propyl, isopropyl, allyl, methallyl, and crotonyl bromides, and iodides. The reaction can be carried out at -20 to 100° C., preferably with stirring between 2-30 hours. After the reaction is terminated the product II is recovered by separating from it the different other products, 1- and 4-substituted triazolobenzodiazepines, by chromatography.

In carrying out the process (B) of this invention, a selected 1,3-dihydro-5-phenyl-2H-1,4-benzodiazepine-2-thione (IA), in an inert organic solvent, preferably in a lower alkanol, e.g., methanol, ethanol, 1-propanol, 2-propanol, 1-butano, 2-butanol, 1,1-dimethylethanol, dioxane, tetrahydrofuran, dimethyl sulfoxide or the like is heated to between 60-100° C., preferably to the reflux temperature of the mixture, with alkyl carbazole of Formula III (preferably in excess). The solvent is then removed and the intermediate heated at 180 to 250° either neat or in a higher boiling inert solvent. In the preferred embodiment of this invention the reaction is carried out with nitrogen bubbling through the reaction mixture during a period of 4 to 48 hours. After the reaction is terminated, the product is obtained by concentrating the mixture, and the residue is purified by crystallization. The product, a substituted 2,4-dihydro-2,3-di(alkyl or alkenyl)-6-phenyl-

1H-s-triazolo[4,3-a][1,4]benzodiazepin-1-one II, is obtained.

The following preparations and examples are illustrative of the process and products of the present invention, but are not to be construed as limiting.

PREPARATION 1

3-(7-chloro-5-phenyl-3H-1,4-benzodiazepin-2-yl) carbazic acid ethyl ester

A mixture of 7-chloro-1,3-dihydro-5-phenyl-2H-1,4-benzodiazepine-2-thione (1.43 g.; 0.005 mole), ethyl carbazole (1.29 g.; 0.015 mole) and absolute ethanol (50 ml.) was refluxed for 14 hours with a slow stream of nitrogen bubbling through the mixture. The mixture was then concentrated to give a residue and the residue was crystallized from methylene chloride-ethyl acetate to give 1.38 g. (77% yield) of 3-(7-chloro-5-phenyl-3H-1,4-benzodiazepin-2-yl)carbazic acid ethyl ester of melting point 195.5-197.5° C. (dec.). The analytical sample, prepared by recrystallization from the above solvent mixture, had a melting point of 198-199° C. (dec.).

Analysis.—Calcd. for $C_{18}H_{17}ClN_4O_2$ (percent): C, 60.59; H, 4.80; Cl, 9.94; N, 15.70. Found (percent): C, 60.57; H, 4.73; Cl, 9.98; N, 15.40.

PREPARATION 2

8-chloro-2,4-dihydro-6-phenyl-1H-s-triazolo[4,3-a][1,4]benzodiazepin-1-one

3 - (7 - chloro - 5 - phenyl-3H-1,4-benzodiazepin-2-yl) carbazic acid ethyl ester (0.5 g.; 0.0014 mole) was heated under nitrogen at 197-207° C. for 15 minutes. The cooled melt was crystallized from ethanol to give 0.28 g. of 8-chloro - 2,4 - dihydro - 6 - phenyl-1H-s-triazolo[4,3-a][1,4]benzodiazepin-1-one, which on recrystallization from ethanol had a melting point of 255-256° C.

Analysis.—Calcd. for $C_{16}H_{11}ClN_2O$ (percent): C, 61.84; H, 3.57; Cl, 11.41; N, 18.03. Found (percent): C, 61.44; H, 3.57; Cl, 11.46; N, 17.90.

PREPARATION 3

3-[7-chloro-5-(o-chlorophenyl)-3H-1,4-benzodiazepin-2-yl]carbazic acid ethyl ester

45 In the manner given in Preparation 1, 5.75 g. (0.02 mole) of 7 - chloro - 1,3 - dihydro-5-(o-chlorophenyl)-2H-1,4-benzodiazepine-2-thione and 5.25 g. (0.06 mole) of ethyl carbazole in 200 ml. of absolute ethanol was refluxed for 24 hours in a nitrogen atmosphere. The mixture was then concentrated to give a residue which was recrystallized from 2-propanol to give 3-[7-chloro-5-(o-chlorophenyl) - 3H - 1,4-benzodiazepin - 2 - yl]carbazic acid ethyl ester of melting point 191-192° C.

Analysis.—Calcd. for $C_{18}H_{16}Cl_2N_4O_2$ (percent): C, 55.20; H, 4.12; N, 14.32; Cl, 18.12. Found (percent): C, 55.26; H, 3.96; N, 4.41; Cl, 17.88.

PREPARATION 4

2,4-dihydro-8-chloro-6-(o-chlorophenyl)-1H-s-triazolo[4,3-a][1,4]benzodiazepin-1-one

60 3 - [7 - chloro - 5 - (o - chlorophenyl)-3H-1,4-benzodiazepin-2-yl]carbazic acid ethyl ester (3.5 g. 0.01 mole) was heated under nitrogen at 225-230° for 30 minutes. The cooled melt was crystallized from ethanol (75 ml.) to give 2.5 g. (80%) of white crystals of 2,4-dihydro-8-chloro - 6 - (o - chlorophenyl)-1H-s-triazolo[4,3-a][1,4]benzodiazepin-1-one.

Analysis.—Calcd. for $C_{16}H_{10}Cl_2N_4O$ (percent): C, 55.26; H, 4.12; N, 14.32; Cl, 18.12. Found (percent): C, 54.79; H, 4.05; N, 14.47; Cl, 18.34.

In the manner given in the preceding preparations other 65 2,4 - dihydro - 6 - phenyl - 1H - s - triazolo[4,3-a][1,4]benzodiazepin-1-one (I) starting compounds can be syn-

thesized. Representative starting compounds of Formula I include:

8-nitro-2,4-dihydro-6-(o-chlorophenyl)-1H-s-triazolo[4,3-a][1,4]benzodiazepin-1-one;
8-chloro-2,4-dihydro-6-(2,6-difluorophenyl)-1H-s-triazolo[4,3-a][1,4]benzodiazepin-1-one;
9-bromo-2,4-dihydro-6-(m-cyanophenyl)-1H-s-triazolo[4,3-a][1,4]benzodiazepin-1-one;
10-trifluoromethyl-2,4-dihydro-6-(p-ethylphenyl)-1H-s-triazolo[4,3-a][1,4]benzodiazepin-1-one;
7-methylthio-10-iodo-2,4-dihydro-6-(phenyl)-1H-s-triazolo[4,3-a][1,4]benzodiazepin-1-one;
7,8-dicyano-10-iodo-2,4-dihydro-6-(m-propylthiophenyl)-1H-s-triazolo[4,3-a][1,4]benzodiazepin-1-one;
4,7,9-trimethyl-2,4-dihydro-6-(phenyl)-1H-s-triazolo[4,3-a]benzodiazepin-1-one;
10-isopropyl-2,4-dihydro-6-(p-bromophenyl)-1H-s-triazolo[4,3-a][1,4]benzodiazepin-1-one;
8-ethylsulfonyl-2,4-dihydro-6-(m-trifluoromethyl)-1H-s-triazolo[4,3-a][1,4]benzodiazepin-1-one;
7-propylsulfinyl-2,4-dihydro-6-(2,4-diethoxyphenyl)-1H-s-triazolo[4,3-a][1,4]benzodiazepin-1-one;
7-dipropylamino-2,4-dihydro-6-(p-ethylsulfinylphenyl)-1H-s-triazolo[4,3-a][1,4]benzodiazepin-1-one;
8-nitro-2,4-dihydro-6-(o-formamidophenyl)-1H-s-triazolo[4,3-a][1,4]benzodiazepin-1-one;
10-(N-methyl acetamido-2,4-dihydro-6-(phenyl)-1H-s-triazolo[4,3-a][1,4]benzodiazepin-1-one;
9-dimethylamino-2,4-dihydro-6-(o-chlorophenyl)-1H-s-triazolo[4,3-a][1,4]benzodiazepin-1-one;
7,9-diethoxy-2,4-dihydro-6-(p-iodophenyl)-1H-s-triazolo[4,3-a][1,4]benzodiazepin-1-one;
and the like.

PREPARATION 6

7-chloro-2-(1,2-dimethylhydrazino)-5-phenyl-1,4-benzodiazepine

To a suspension of 10.8 g. (0.037 mole) of 7-chloro-1,3-dihydro-5-phenyl-2H-1,4-benzodiazepin-2-thione in 400 ml. of methanol and 28 ml. (0.2 mole) of triethylamine under nitrogen was slowly added with stirring at room temperature a suspension of 10 g. (0.075 mole) of symdimethylhydrazine dihydrochloride in 200 ml. of methanol. The mixture was stirred under reflux for 10 hours, allowed to stand at room temperature for 3 days, filtered, and evaporated to dryness in vacuo. The residue was shaken with water and neutralized with acetic acid. The resulting solid was collected, washed with water and dried. Recrystallization from 2-propanol yielded 10.1 g. (95%) of light greenish crystals, of melting point 167-175°. A second recrystallization from 2-propanol gave white crystals of 7-chloro-2-(1,2-dimethylhydrazino)-5-phenyl-1,4-benzodiazepine of melting point 175.5-176.5° C.

Analysis.—Calcd. for $C_{17}H_{17}ClN_4$ (percent): C, 65.28; H, 5.48; Cl, 11.33; N, 17.91. Found (percent): C, 65.89; H, 5.42; Cl, 11.32; N, 18.01.

EXAMPLE 1

8-chloro-6-(o-chlorophenyl)-2,3-dihydro-2-methyl-1H-s-triazolo[4,3-a][1,4]benzodiazepin-1-one; 8-chloro-6-(o-chlorophenyl)-2,4-dihydro-2,4-dimethyl-1H-s-triazolo[4,3-a][1,4]benzodiazepin-1-one; and 8-chloro-6-(o-chlorophenyl)-2,3-dihydro-2,3-dimethyl-1H-s-triazolo[4,3-a][1,4]benzodiazepin-1-one.

A stirred solution of 8-chloro-2,4-dihydro-6-(o-chlorophenyl)-1H-s-triazolo[4,3-a][1,4]benzodiazepin-1-one (8.70 g., 0.03 mole) in dimethylformamide (150 ml.), under nitrogen, was treated with 2.2 ml. (0.03 mole) of thallous ethoxide. The resulting mixture was stirred for 15 minutes, 2.4 ml. (0.038 mole) of methyl iodide was added dropwise to the above mixture and stirring was continued at room temperature for 4 hours. The resulting reaction mixture was filtered and the residue

was washed thoroughly with dimethylformamide. The filtrate was diluted with 300 ml. of water, providing a yellow solid. This was extracted with ether (thrice) and the ether solution was washed with water, dried, filtered, and concentrated in vacuo giving an orange oil which by thin layer chromatography on silica gel (50% ethyl acetate/cyclohexane) appeared to be a mixture of three compounds. The oil was chromatographed on silica gel (2 kg.) and eluted with 50% ethyl acetate-cyclohexane taking 150 ml. fractions.

Fractions 35-44 were combined and crystallized from 2-propanol to give 550 mg. of 8-chloro-2,3-dihydro-2,3-dimethyl-6-(o-chlorophenyl)-1H-s-triazolo[4,3-a][1,4]benzodiazepin-1-one of melting point 208-210° C.

Analysis.—Calcd. for $C_{18}H_{14}Cl_2N_4O$ (percent): C, 57.90; H, 3.78; N, 15.00; Cl, 19.00. Found (percent): C, 57.70; H, 3.91; N, 14.96; Cl, 19.17.

The other products were isolated and had the following characteristics:

Fractions 68-77 were combined and crystallized from ether to give 1.1 g. of 8-chloro-6-(o-chlorophenyl)-2,4-dihydro-2,4-dimethyl-1H-s-triazolo[4,3-a][1,4]benzodiazepin-1-one of melting point 153-155° C.

Analysis.—Calcd. for $C_{18}H_{14}Cl_2N_4O$ (percent): C, 57.90; H, 3.78; N, 15.00; Cl, 19.00. Found (percent): C, 57.94; H, 3.70; N, 15.25; Cl, 19.09.

Fractions 99-120 were combined and crystallized from ether-Skelly B hexanes to give 3.3 g. of 8-chloro-6-(o-chlorophenyl)-2,4-dihydro-2-methyl-1H-s-triazolo[4,3-a][1,4]benzodiazepin-1-one of melting point 82-84°.

Analysis.—Calcd. for $C_{17}H_{12}Cl_2N_4O$ (percent): C, 56.85; H, 3.38; N, 15.59; Cl, 19.71. Found (percent): C, 56.45; H, 3.51; N, 15.12; Cl, 19.33.

EXAMPLE 2

8-chloro-2,3-dihydro-2,3-dipropyl-6-phenyl-1H-s-triazolo[4,3-a][1,4]benzodiazepin-1-one

In the manner given in Example 1, 8-chloro-2,4-dihydro-6-phenyl-1H-s-triazolo[4,3-a][1,4]benzodiazepin-1-one can be treated with thallous ethoxide and then with propyl bromide to give after chromatographic separation 8-chloro-2,3-dihydro-2,3-dipropyl-6-phenyl-1H-s-triazolo[4,3-a][1,4]benzodiazepin-1-one.

EXAMPLE 3

8-chloro-2,3-dihydro-2,3-diethyl-6-(2,6-difluorophenyl)-1H-s-triazolo[4,3-a][1,4]benzodiazepin-1-one

In the manner given in Example 1, 8-chloro-2,4-dihydro-6-(2,6-difluorophenyl)-1H-s-triazolo[4,3-a][1,4]benzodiazepin-1-one can be treated with thallous ethoxide and then with ethyl iodide to give after chromatographic separation 8-chloro-2,3-dihydro-2,3-diethyl-6-(2,6-difluorophenyl)-1H-s-triazolo[4,3-a][1,4]benzodiazepin-1-one.

EXAMPLE 4

8-nitro-2,3-dihydro-2,3-dimethyl-6-(o-chlorophenyl)-1H-s-triazolo[4,3-a][1,4]benzodiazepin-1-one

In the manner given in Example 1, 8-nitro-2,4-dihydro-6-(o-chlorophenyl)-1H-s-triazolo[4,3-a][1,4]benzodiazepin-1-one can be treated with thallous ethoxide and then with methyl iodide to give after chromatographic separation 8-nitro-2,3-dihydro-2,3-dimethyl-6-(o-chlorophenyl)-1H-s-triazolo[4,3-a][1,4]benzodiazepin-1-one.

EXAMPLE 5

10-isopropyl-2,3-dihydro-2,3-diisopropyl-6-(p-bromophenyl)-1H-s-triazolo[4,3-a][1,4]benzodiazepin-1-one

In the manner given in Example 1, 10-isopropyl-2,4-dihydro-6-(p-bromophenyl)-1H-s-triazolo[4,3-a][1,4]benzodiazepin-1-one can be treated with thallous ethoxide and then with isopropyl bromide to give after

9

chromatographic separation 10 - isopropyl - 2,3 - dihydro - 2,3 - diisopropyl - 6-(p-bromophenyl)-1H-s-triazolo[4,3-a][1,4]benzodiazepin-1-one.

EXAMPLE 6

8 - ethylsulfonyl - 2,3 - dihydro - 2,3 - diallyl - 6 - (m-trifluoromethylphenyl) - 1H-s-triazolo[4,3 - a][1,4]benzodiazepin-1-one

In the manner given in Example 1, 8-ethylsulfonyl-2,4-dihydro-6 - (m-trifluoromethylphenyl)-1H-s-triazolo[4,3-a][1,4]benzodiazepin-1-one can be treated with thallous ethoxide and then with allyl bromide to give after chromatographic separation 8 - ethylsulfonyl-2,3-dihydro-2,3 - diallyl - 6 - (m-trifluoromethylphenyl)-1H-s-triazolo[4,3-a][1,4]benzodiazepin-1-one.

EXAMPLE 7

4,7,9-trimethyl-2,3-dihydro-2,3-dicrotyl-6-phenyl-1H-s-triazolo[4,3-a][1,4]benzodiazepine-1-one

(A) A mixture of 3,6,8-trimethyl-1,3-dihydro-5-phenyl-2H-1,4-benzodiazepine-2-thione, 2,3-dicrotyl carbazic acid ethyl ester, and ethanol can be refluxed for 14 hours under nitrogen to give 3-[3,6,8-trimethyl-5-phenyl-3H-1,4-benzodiazepin-2-yl]-2,3-dicrotyl carbazic acid ethyl ester.

(B) This ester can be heated to about 250° C. in a nitrogen atmosphere for 15 minutes, the melt is cooled and recrystallized from ethanol to give 4,7,9-trimethyl-2,3 - dihydro - 2,3 - dicrotyl - 6 - phenyl - 1H-s-triazolo[4,3-a][1,4]benzodiazepin-1-one.

EXAMPLE 8

8-nitro-2,3-dihydro-2,3-diethyl-6-(o-chlorophenyl)-1H-s-triazolo[4,3-a][1,4]benzodiazepin-1-one

(A) A mixture of 7 - nitro- 1,3 - dihydro - 5-(o-chlorophenyl) - 2H - 1,4 - benzodiazepine - 2 - thione, 2,3 - dimethylcarbazic acid ethyl ester, and ethanol can be refluxed for 14 hours under nitrogen to give 3-[7-nitro-5-(o-chlorophenyl) - 3H - 1,4 - benzodiazepin - 2 - yl] carbazic acid ethyl ester.

(B) This ester can be heated to about 250° C. in a nitrogen atmosphere, for 15 minutes, the melt is cooled and recrystallized from ethanol to give 8-nitro-2,3-dihydro-2,3-diethyl-6-(o-chlorophenyl) - 1H - s - triazolo[4,3-a][1,4]benzodiazepin-1-one.

EXAMPLE 9

8-chloro - 2,3 - dihydro - 2 - methyl-3-allyl-6-(o-chlorophenyl) - 1H - s - triazolo[4,3-a][1,4]benzodiazepine-1-one

(A) A mixture of 7-chloro-1,3-dihydro-5-(o-chlorophenyl) - 2H - 1,4-benzodiazepine-2-thione, 2-methyl-3-allylcarbazic acid ethyl ester, and ethanol can be refluxed for 14 hours under nitrogen to give 3-[7-chloro-5-(o-chlorophenyl)-3H-1,4-benzodiazepin-2-yl] - 2 - methyl-3-allylcarbazic acid ethyl ester.

(B) This ester can be heated to about 250° C. in a nitrogen atmosphere, for 15 minutes, the melt is cooled and recrystallized from ethanol to give 8-chloro-2,3-dihydro-2-methyl-3-allyl - 6 - (o - chlorophenyl)-1H-s-triazolo[4,3-a][1,4]benzodiazepin-1-one.

EXAMPLE 11

7,8-dicyano - 2,3 - dihydro-2-ethyl-3-propyl-6-(m-propylthiophenyl) - 1H-s-triazolo[4,3-a][1,4]benzodiazepin-1-one

(A) A mixture of 6,7-dicyano-1,3-dihydro-5-(m-propylthiophenyl)-2H-1,4-benzodiazepine-2-thione, 2-ethyl-3-propyl carbazic acid ethyl ester, and ethanol can be refluxed for 14 hours under nitrogen to give 3-[6,7-dicyano - 5 - (m-propylthiophenyl)-3H-1,4-benzodiazepin-2-yl]-2-ethyl-3-propyl-carbazic acid ethyl ester.

(B) This ester can be heated to about 250° C. in a nitrogen atmosphere, for 15 minutes, the melt is cooled and recrystallized from ethanol to give 7,8-dicyano-2,3-

10

dihydro-2-ethyl - 3 - propyl-6-(m-propylthiophenyl)-1H-s-triazolo[4,3-a][1,4]benzodiazepin-1-one.

EXAMPLE 12

9-dimethylamino - 2,3 - dihydro-2,3-diallyl-6-(o-chlorophenyl) - 1H - s - triazolo[4,3-a][1,4]benzodiazepine-1-one

(A) A mixture of 8-dimethylamino - 1,3 - dihydro-5-(o-chlorophenyl)-2H-1,4-benzodiazepine-2-thione, 2,3-diallylcarbazic acid ethyl ester, and ethanol can be refluxed for 14 hours in nitrogen to give 3-[8-dimethylamino-5-(o-chlorophenyl) - 1,3 - dihydro-3H-1,4 - benzodiazepin-2-yl]-2,3-diallyl carbazic acid ethyl ester.

(B) This ester can be heated to about 250° C. in a nitrogen atmosphere, for 15 minutes the melt is cooled and recrystallized from ethanol to give 9-dimethylamino-2,3-dihydro - 2,3 - diallyl - 6 - (o-chlorophenyl)-1H-s-triazolo[4,3-a][1,4]benzodiazepin-1-one.

EXAMPLE 13

8-chloro-2,3-dihydro-2,3-dimethyl-6-phenyl-1H-s-triazolo[4,3-a][1,4]benzodiazepin-1-one

A mixture of 6-chloro-2-(1,2-dimethylhydrazino)-5-phenyl-1,4-benzodiazepine (preparation 6) and triethylamine in tetrahydrofuran can be cooled to -78° and a slight excess of phosgene added. Warming to room temperature, evaporating, washing with water and crystallizing the resulting solid will yield 8-chloro-2,3-dihydro-2,3-dimethyl-6-phenyl - 1H - s - triazolo[4,3-a][1,4]benzodiazepin-1-one.

In the manner illustrated by the foregoing examples other compounds of configuration II can be prepared. Representative examples are:

8-nitro-2,3-dihydro-2-methallyl-3-methyl-6-(o-chlorophenyl)-1H-s-triazolo[4,3-a][1,4]benzodiazepin-1-one;

8-chloro-2,3-dihydro-2,3-dicrotyl-6-(2,6-difluorophenyl)-1H-s-triazolo[4,3-a][1,4]benzodiazepin-1-one;

9-bromo-2,3-dihydro-2-ethyl-3-isopropyl-6-(m-cyanophenyl)-1H-s-triazolo[4,3-a][1,4]benzodiazepin-1-one;

7,8-dicyano-2,3-dihydro-2,3-diallyl-6-(m-propylthiophenyl)-1H-s-triazolo[4,3-a][1,4]benzodiazepin-1-one;

8-ethylsulfonyl-2,3-dihydro-2,3-diethyl-6-(m-trifluoromethylphenyl)-1H-s-triazolo[4,3-a][1,4]benzodiazepin-1-one;

7-dipropylamino-2,3-dihydro-2,3-dimethyl-6-(p-ethylsulfonylphenyl)-1H-s-triazolo[4,3-a][1,4]benzodiazepin-1-one;

10-acetamido-2,3-dihydro-2,3-diallyl-6-(phenyl)-1H-s-triazolo[4,3-a][1,4]benzodiazepin-1-one;

7,9-dieoxy-2,3-dihydro-2,3-propyl-6-(p-iodophenyl)-1H-s-triazolo[4,3-a][1,4]benzodiazepin-1-one;

10-trifluoromethyl-2,3-dihydro-2-methyl-3-allyl-6-p-ethylphenyl)-1H-s-triazolo[4,3-a][1,4]benzodiazepin-1-one;

4,7,9-trimethyl-2,3-dihydro-2,3-dimethyl-6-(phenyl)-1H-s-triazolo[1,2-a][1,4]benzodiazepin-1-one;

10-isopropyl-2,3-dihydro-2,3-diethyl-6-p-bromophenyl)-1H-s-triazolo[4,3-a][1,4]benzodiazepin-1-one;

4-propyl-8-methyl-2,3-dihydro-2-allyl-3-crotyl-6-(m-fluorophenyl)-1H-s-triazolo[4,3-a][1,4]benzodiazepin-1-one;

7-dipropylamino-2,3-dihydro-2,3-dimethyl-6-(p-ethylsulfinylphenyl)-1H-s-triazolo[4,3-a][1,4]benzodiazepin-1-one;

9-dimethylamino-2,3-dihydro-2,3-dicrotyl-6-(o-chlorophenyl)-1H-s-triazolo[4,3-a][1,4]benzodiazepin-1-one;

and the like.

The Compounds II of the foregoing examples and lists can be converted to acid addition salts by reaction with stoichiometrically calculated amounts of selected acids in

11

water, ethanol, or with the hydrogen halides in particular, in ether. In this manner the hydrochlorides, hydrobromides, hydroiodides, sulfates, phosphates, acetates, propionates, lactates, tartrates, citrates, maleates, malates, pamoates, benznesulfonates, p-toluenesulfonates, methanesulfonates, cyclohexanesulfamates, salicylates and the like of the foregoing 2,3-alkyl- or alkylene substituted 2,3-dihydro - 6 - phenyl-1H-s-triazolo[4,3-a][1,4]benzodiazepin-1-ones can be obtained.

What is claimed is:

1. A compound selected from the group consisting of 2,3-disubstituted - 2,3 - dihydro - 1H - s - triazolo[4,3-a][1,4]benzodiazepin-1-one of the Formula II:

5 10 15 20 25 30 35 40 45

12

4. A process for the preparation of 2,3-disubstituted-2,3-dihydro - 1H - s - triazolo[4,3-a][1,4]benzodiazepin-1-one of the Formula II:

II

wherein R and R0 are selected from the group consisting of alkyl of 1 to 3 carbon atoms, inclusive, and alkenyl of 3 to 4 carbon atoms, inclusive; wherein R2, R3, R4, and R5 are selected from the group consisting of hydrogen, alkyl defined as above, amino, halogen, nitro, cyano, trifluoromethyl, and alkoxy, alkylthio, alkylsulfonyl, and alkylsulfinyl, in which the carbon moieties are of 1 to 3 carbon atoms, inclusive, and dialkylamino, in which the alkyl group is defined as above; which comprises: treating a 2,4-dihydro-1H-s-triazolo[4,3-a][1,4]benzodiazepin-1-one of the Formula I:

I

wherein R1, R2, R3, R4, and R5 are defined as above, with thallous ethoxide, in an organic solvent, at room temperature, and treating the resulting product with an alkyl or alkenyl bromide or iodide, in which alkyl and alkenyl are defined as above, to obtain the compound of Formula II above.

wherein R and R0 are selected from the group consisting of alkyl of 1 to 3 carbon atoms, inclusive, and alkenyl of 3 to 4 carbon atoms, inclusive; wherein R1 is selected from the group consisting of hydrogen, alkyl of 1 to 3 carbon atoms, inclusive, and alkenyl of 3 to 4 carbon atoms, inclusive; wherein R2, R3, R4, and R5 are selected from the group consisting of hydrogen, alkyl defined as above, amino, halogen, nitro, cyano, trifluoromethyl, and alkoxy, alkylthio, alkylsulfonyl, and alkylsulfinyl, in which the carbon moieties are of 1 to 3 carbon atoms, inclusive, and dialkylamino, in which the alkyl group is defined as above; and the pharmacologically acceptable acid addition salts thereof.

2. The compound according to claim 1 wherein R and R0 are methyl, R1, R3, and R5 are hydrogen, R2 is o-chloro, R4 is 8-chloro and the compound is therefore 8-chloro-2,3 - dihydro - 2,3 - dimethyl - 6 - (o-chlorophenyl)-1H-s-triazolo[4,3-a][1,4]benzodiazepin - 1 - one.

3. The compound according to claim 1 wherein R and R0 are methyl, R1, R2, R3, and R5 are hydrogen, R4 is 8-chloro and the compound is therefore 8-chloro-2,3-dihydro - 2,3 - dimethyl - 6 - phenyl - 1H - s - triazolo[4,3-a][1,4]benzodiazepin-1-one.

UNITED STATES PATENT OFFICE
CERTIFICATE OF CORRECTION

PATENT NO. 3,772,318
DATED November 13, 1973
INVENTOR(S) Robert B. Moffett

It is certified that error appears in the above-identified patent and that said Letters Patent are hereby corrected as shown below:

Column 1, line 38, "inclusive" should read -- inclusive --.
Column 2, line 40-50, Formula II should appear as shown below
instead of as in the patent:

Column 2, line 50-65, Formula II should appear as shown below
instead of as in the patent:

UNITED STATES PATENT OFFICE
CERTIFICATE OF CORRECTION

PATENT NO.

3,772,318

DATED

November 13, 1973

INVENTOR(S)

Robert B. Moffett

It is certified that error appears in the above-identified patent and that said Letters Patent are hereby corrected as shown below:

line 75,
"2-4-dihydro" should read -- 2,4-dihydro --. Column 6, line 1,
"bnezodiazepin" should read -- benzodiazepin --. Column 7,
line 8, "bezodiazepin" should read -- benzodiazepin --. Column
10, line 57, "p-ethylphenyl)" should read -- (p-ethylphenyl) --;
line 61, "p-bromophenyl)" should read -- (p-bromophenyl) --.
Column 11, line 5, "beneznesulfonates" should read -- benzene-
sulfonates --.
